UNITED STATES PATENT OFFICE.

WILLIAM SOBEY, OF RACINE, WISCONSIN.

CULTIVATOR.

SPECIFICATION forming part of Letters Patent No. 794,129, dated July 4, 1905.

Application filed December 7, 1903. Serial No. 184,031.

To all whom it may concern:

Be it known that I, WILLIAM SOBEY, a citizen of the United States, and a resident of Racine, county of Racine, and State of Wisconsin, have invented certain new and useful Improvements in Cultivators, of which the following is declared to be a full, clear, and exact description.

The invention relates to wheel-cultivators which carry independent shovel-beams for opposite sides of the plant row. In such cultivators the gang-beams are swung at their forward ends to the main frame and are adjustably supported at their rear ends. The axle usually comprises an elevated horizontal section swiveled to the frame and depending wheel-sections, so that the axle is arch-shaped to straddle the row. The wheel-sections of the axle are usually laterally adjustable with reference to the horizontal central portion to accommodate the cultivator for rows of different width. Suitable adjusting shift mechanism or regulating devices are provided for the gang-beams, which are preferably under control from the driver's seat and arranged to be releasably locked in any adjusted position.

The present invention seeks to provide simple and effective shifter mechanism which is entirely independent of the regulating devices for the gang-beams and by which the position of the depending portions of the arched axle may be readjusted with reference to the frame, and thereby properly balance the machine for operators of different weight. The selected means does not require the removal of securing-bolts or like expedients, but by simple shift accomplishes the desired end. A suitable actuating-lever carried on the frame enables the driver to control the shift at will from his seat. The upper ends of the stub-axes are mounted in peculiar fashion, so that they can be adjusted not only laterally for different widths of tread, but through their swiveled connections with the main frame can quickly readjust in the line of draft, according to the balance established for the driver at his seat.

A further object of the invention is to provide a simple and effective arrangement for

independently mounting the regulating devices for the gang-beams and the adjusting-shifter for the stub-axes. 50

The invention also provides an effective form of swiveled connections for the cultivator-beams by which the latter may be readily 55 adapted for either "level" or "pendulum" swing.

The purpose is also to simplify the union of the separate parts of the arched axles with the frame of the machine; and the invention 60 consists in the features of construction, arrangements, and combinations of parts set forth in the following description, illustrated in the accompanying drawings, and more particularly pointed out in the appended claims. 65

In the drawings, Figure 1 is a side elevation of a cultivator with the present improvements applied. In this figure for the sake of clearness the near wheel is broken away and the draft-evener shown in section. Fig. 2 is a 70 plan view with certain parts omitted. Fig. 3 is a detail view, part in elevation and part in section, of the arched axle and its connections with the frame. Fig. 4 is a detail plan view of the connections between the frame 75 and the sections of the arched axle. Fig. 5 is a detail bottom view of the same. Fig. 6 is a detail section on line 6 6 of Fig. 3. Fig. 7 is a detail section on line 7 7 of Fig. 3. Fig. 8 is a detail view, partly in section and partly 80 in elevation, of the adjusting shifter for the stub-axes. Fig. 9 is a detail view, partly in elevation and partly in section, of the forward swiveled connections for the gang-beams. Fig. 10 is a detail section of the connection 85 shown in Fig. 9. Fig. 11 is a detail front view thereof. Fig. 12 is a detail view in elevation of the swiveled connections for the gang-beams at the rear, and Figs. 13 and 14 are detail sections thereof, taken in plans at 90 right angles to each other.

In the usual manner the carrying-wheels 15 are journaled upon spindles at the lower horizontal terminals of the arched axle. Each depending stub-axle or wheel-section 16 has 95 at its upper end an inwardly-projecting horizontal portion 17, which fits snugly within the horizontal tubular crown-section 18.

Brackets 19 are mounted upon opposite ends of the horizontal axle-section 18 and are provided with solid-ring portions 20 and split-ring portions 21, which embrace the ends of the horizontal axle-section. Bolts 22 extend between the ends of the split-ring portions 21 and serve to securely clamp the brackets 19 in position. Each of the horizontal portions 17 of the axle-sections 16 adjustably extends through a collar 23, which sets within a semi-circular slot or recess 24 in the under face of the adjacent bracket 19 and is held thereby against longitudinal shift. Set-screws 25, threaded through the collars, hold the wheel-sections in adjusted position. The brackets 19 and collars 23, clamped, respectively, to crown-sections 18 and to the horizontal portions 17 of the axle-sections, as described, serve to securely connect the separate sections of the arched supporting-axle. At the same time since collars 23 may freely rotate in the recesses 24 the depending wheel-sections 16 may swivel freely within the horizontal tubular section 18. The "tread" of the cultivator-wheels can be varied at will in keeping the width of the plant row by adjusting the wheel-sections 16 through the collars 23 and tubular axle-section 18 and clamping the same in such adjusted position by set-screws 25. The brackets 19 also preferably serve as connections between the arched axle and the frame of the cultivator and for this purpose are provided at their outer ends with upright and horizontal flanges 26 and 27, forming seats for the side bars 28 of the frame. These flanged portions 26 and 27 preferably diverge rearwardly (see Figs. 2 and 4) in keeping with the arrangement of the side bars and the rearwardly-extending supports 29. The supports 29 are U-shaped in section and rest, as shown, upon the horizontal projections or flanges 27 of the brackets 19, and the forward ends of such supports are adjustably secured to the side bars 28 by straps 30. The rider's seat 31 is carried upon a cross-bar 32, of spring metal, adjustably secured at its ends to the rear portions of the supports 29. The forward converging ends of the side bars 28 are securely fastened to the pole 33. The draft-evener 34 is pivotally supported upon the under side of the pole and affords suitable attachment for the swingletrees.

Split collars 35 are secured by bolts 36 to the lower ends of the depending wheel-sections 16 of the arched axle, and to the bolts 36 are pivoted the rear ends of the brace-links 37. The forward ends of the latter are pivotally connected to the lower ends of the shifter rock-arms 38, which are fixed upon the ends of and depend downwardly from the shifter rock-shaft 39. This shaft extends transversely across the machine at its front portion and is journaled at opposite ends in suitable bearing-boxes 40. The bearing-boxes

40 are provided at their inner ends with up-standing lugs 41, grooved to fit the side bars 28 of the machine-frame and firmly secured thereto by bolts 42. The means for actuating the shifter rock-shaft preferably comprises a hand-lever 43, bolted at its forward end to an extension 44 on the hub of one of the rock-arms 38 and extending rearwardly within reach of the rider.

Means for locking the shifter mechanism in any of its adjusted positions preferably comprises a segmental rack 45, fixed to the end of one of the journal-boxes 40 adjacent the shift-lever, and a co-operating spring-held latch 46, mounted to slide within a bracket 47 on the side of the shift-lever 43, said latch being arranged to engage the teeth of the segmental rack 45. A trip 48 for releasing the latch 47 is pivoted near the end of the hand-lever 43 and is connected to the latch by a link 49. By means of the shifter and operating connections the positions of the wheel-sections of the arched axle relatively to the frame may be quickly and easily adjusted and locked in adjusted position, so that the leverage of the driver's weight upon the pole and other parts in front of the axle is correspondingly adjusted, and in this way the parts may be positioned to properly balance the machine with riders of different weight. Moreover, the adjustment may be easily and readily effected from the rider's seat.

To the under side of the pole and in front of the draft-evener is fixed the transverse cross-shaft or fore-reach 50, upon which are mounted sleeves 51. These sleeves are free to rotate upon the cross-shaft 50, but are adjustably held against longitudinal shift thereon by collars 52 set within slots in the sleeves 51 and held in position by set-screws 53. Each of the horizontal sleeves 51 is provided with a pair of depending lugs 54, between which extends a forwardly-projecting lug 55 upon a vertically-disposed sleeve 56. A bolt 57, extending through the lugs 54 and 55, holds the vertical sleeve 56 in place. Upstanding lugs or projections 58 and 59 upon the horizontal and vertical sleeves 51 and 56 are arranged adjacent each other and are connected by a bolt 60, which extends through an arc-shaped slot 61 in the lug 58.

The lug 55 is elliptical in section or tapers toward its edges, and the bolt 57 loosely fits the opening in this lug, so that when the nut on bolt 60 is loose the sleeve 56 may oscillate from side to side to a limited extent upon the pin 57. By tightening the nut on bolt 60 the vertical sleeve 56 is of course held against oscillation. The round upturned ends of the cultivator-beams 62 extend through the vertical sleeves 56 and are adjustably supported therein by collars 63, which are provided with recessed flanged portions 64, arranged to engage an annular flange or lip 65 upon the

lower end of the sleeve 56. The collars 63 are secured to the ends 61 of the gang-beams by set-screws 66. The height of the forward ends of the gang-beams may be adjusted through the collars 63 and sleeves 56 and then held in adjusted position by the set-screws 66. At the same time the forward ends of the gang-beams are vertically swiveled within the sleeves 56, so that the gang-beams may swing horizontally within the sleeve 56 to a limited extent. At the rear each gang-beam 62 is connected to the lower end of a suspension-rod 67, the upper curved end of which is pivoted to the outer end of an upwardly-extending radius-arm 68. The heel of the radius-arm terminates in a horizontal sleeve 69, (see Fig. 3,) which is journaled upon a pivot-bolt 70, passing through ears 71 on the upper face of the adjacent bracket 19. Shovels 72 are secured in the usual manner by shanks 73 to the gang-beams, and the supporting-rods 67 are provided with the usual operating-handles 74.

The joint between the lower ends of the suspension-rods 67 and the gang-beam 62 is formed as more clearly shown in Figs. 12, 13, and 14. Each gang-beam consists of separate connected members, and a bracket 75 is pivoted to a cross-bolt 76, extending between the separate members of the beam. A sleeve 77 extends through the bore of the bracket 75 and between the members of the gang-beam, so that the latter cannot be drawn together sufficiently close to prevent the free pivotal movement of the bracket. The ends of the pivoted portion of the bracket are somewhat conical in outline and set within similarly-shaped recesses in pieces 78, which are preferably grooved, as shown upon their outer faces, so as to fit snugly against the sides of the separate members of the gang-beam. The lower end of the suspension-rod 67 is pivotally connected to the bracket by a bolt 79. A second bolt 80 above the bolt 79 extends through a hole in the suspension-rod and through a segmental slot in the bracket 75. These pivotal connections for the forward and rear ends of the gang-beams may be adjusted to give either what is known as the "level" swing or the so-called "pendulum" swing. All the changes may be made by simply tightening the nut on one bolt and loosening that on the other. For example, if the nut on the bolt 80 is tight, so that the bracket 75 and suspension-rod 67 are rigidly secured together, and the nut on bolt 60 loose, so that the vertical sleeve 56 is free to oscillate from side to side, the gang-beams 62 will swing in the arc of a circle as they are shifted to and fro by the feet of the operator within the stirrups 82—that is to say, the gang-beams rise as they approach the end of their lateral swing. On the other hand, if the nut on bolt 60 is tight, so that the vertical sleeve 56 cannot oscillate,

and the nut on bolt 80 is loose the gang-beams 65 will then swing in a horizontal plane with their forward ends turning within the sleeves 56. The first adjustment described gives the so-called "pendulum" swing and the second the "level" swing. At the same time these 70 joints for supporting the gang-beams permit the free up-and-down movement thereof as they pass over the ground and as they are thrown into and out of operative position.

The regulating devices for each gang-beam 75 preferably comprises a heavy spring 83, connected by a chain 84 to the upper end of the radius-arm 68. The forward end of each spring 83 is connected to the upper arm of the shifter 85, which is loosely journaled to rotate 80 upon the shaft 39. (See Fig. 8.) Each shifter is provided with a recessed flange 86, arranged to engage an annular lip 87 upon the inner end of the adjacent bearing-box 40, and is held thereby against longitudinal shift. To the 85 lower arms of the shift-levers 85 are connected links 88, which extend rearwardly through openings 89, formed in upwardly-projecting portions 90 upon the brackets 19. These links 88 are provided at their rear ends with handles 91, by which they may be readily controlled from the driver's seat, and upon their under edge with rack-teeth 92, arranged to engage the edges of the openings 89 to hold the links and the regulating devices in adjusted position.

It will be observed that both the regulating devices for the gang-beams and the shift mechanism for the stub-axles may be easily and conveniently regulated from the driver's seat and that each of these adjustments is entirely independent of the other. The independence of these separate shift mechanisms is essential, since it is often necessary to adjust one without effecting the adjustment of the other. In 100 operation the wheel-sections are first adjusted to properly balance the weight of the rider, and the regulating devices for the plow-beams are then free to be independently adjusted as may be desired. The brackets 19 are provided 105 with rearwardly-extending notched projections 93, within which the suspension-rods 67 are seated when the shovel-beams are in raised position.

It is obvious that numerous changes may be 115 made in the details of structure without departure from the essentials of the invention.

Having thus described my invention, what I claim as new, and desire to secure by Letters Patent, is—

1. In cultivators, the combination with the frame and shovel-beam hung therefrom, of an arched supporting-axle comprising separate depending wheel-sections swiveled to the frame, regulating devices connected to said 125 shovel-beams, shifters connected to said regulating devices and an independently-movable shifter connected to both of said depending

wheel-sections, operating-handles for said shifters under control from the driver's seat and means for locking said shifters in adjusted position.

- 5 2. In cultivators, the combination with a frame and shovel-beams hung therefrom, of an arched supporting-axle comprising separate depending wheel-sections swiveled to the frame, spring-regulators connected to said shovel-beams, shift-levers mounted at the fore end of the frame and connected to said regulators, operating-handles connected to said shifters and extending rearwardly within reach of the rider, means for locking said shifters in adjusted position, a shift mechanism independent of said beam-regulators connected to both of the depending wheel-sections of said arched axle and an operating-handle for said shift mechanism under control from the driver's seat.

3. In cultivators, the combination with the frame and shovel-beam hung therefrom, of an arched supporting-axle swiveled to the frame and having depending wheel-sections, a cross rock-shaft journaled at the fore part of the frame, rock-arms fixed to said shaft and connected to said wheel-sections, an operating-lever for said shaft, means for locking the same in adjusted position, a regulator connected to said shovel-beam, an adjusting shifter for said regulator movable independently of said rock-shaft and an operating-handle for said shifter.

4. In cultivators, the combination with the frame and shovel-beam hung therefrom, of an arched axle swiveled to the frame and having depending wheel-sections, a cross rock-shaft journaled at the fore part of the frame and connected to said wheel-sections, regulators for said shovel-beams, shift-levers pivoted on the forward part of the frame and connected to said regulators and independently-movable operating-handles for said shift-levers and said rock-shaft extending rearwardly within reach of the rider.

5. In cultivators, the combination with the main frame and shovel-beam hung therefrom, of an arched supporting-axle swiveled to the frame and provided with depending wheel-sections, a cross rock-shaft journaled on the fore part of the frame, rock-arms fixed to said shaft and connected to said wheel-sections, pivoted radius-arms supporting the rear ends of said shovel-beams, spring-regulators connected to said radius-arms, shift-levers pivoted at the fore part of the frame and connected to said spring-regulators, independently-movable operating-handles connected to said shift-levers and to said rock-shaft and extending rearwardly therefrom and means for locking said operating-handles in adjusted position.

6. In cultivators, the combination with the main frame, shovel-beams hung therefrom and

regulating devices for said shovel-beams, of an arched supporting-axle comprising separate depending wheel-sections horizontally swiveled to the frame and a common shifter movable independently of said beam-regulating devices connected to both of said wheel-sections to simultaneously adjust the same relatively to said frame.

7. In cultivators, the combination with the main frame, shovel-beams hung therefrom and regulating devices for said shovel-beams, of an arched supporting-axle horizontally swiveled to the frame and provided with depending wheel-sections, a common shifter movable independently of said beam-regulating devices and connected to both of said wheel-sections for adjusting the same, an operating-handle for said shifter under control from the driver's seat on the machine and a releasable lock for holding the parts in adjusted position.

8. In cultivators, the combination with the main frame, shovel-beams hung therefrom and regulating devices for said shovel-beams, of an arched supporting-axle horizontally swiveled at its upper end to the frame and provided with depending wheel-sections, a shifter movable independently of said beam-regulating devices comprising a rock-shaft journaled on the frame, rock-arms fixed to said shaft and links connecting said rock-arms to said wheel-sections, an operating-lever for said rock-shaft and a releasable lock for holding the parts in adjusted position.

9. In cultivators, the combination with the main frame, shovel-beams hung therefrom and regulating devices for said shovel-beams, of an arched axle comprising separate depending wheel-sections, each of said sections having a laterally-adjustable, horizontally-swiveled connection with the main frame, a common shifter movable independently of said beam-regulating devices and connected to the lower portions of both of said wheel-sections to simultaneously adjust the same, an operating-handle for said shifter and means for holding the parts in adjusted position.

10. In cultivators, the combination with the main frame, shovel-beams hung therefrom and regulating devices for said shovel-beams, of an arched supporting-axle comprising separate wheel-sections horizontally swiveled at their upper ends to the main frame, rotatable collars through which the upper, horizontal portions of the wheel-sections extend and to which said horizontal portions are adjustably secured, means for holding said collars against longitudinal movement, adjusting connections between the lower ends of said wheel-sections and the main frame and means movable independently of said beam-regulating devices for shifting said adjusting connections.

11. In cultivators, the combination with the main frame, shovel-beams hung therefrom and regulating devices for said shovel-beams, of an

arched axle comprising a central, crown-section secured to the frame and depending horizontally swiveled and laterally adjustable in said crown-section, a 5 shifter movable independently of said beam-regulating devices and comprising a rock-shaft journaled on the frame, rock-arms fixed to said shaft and links connecting said arms and the lower portions of said wheel-sections, 10 an operating-lever for said rock-shaft and a releasable locking device for holding the parts in adjusted position.

12. In cultivators, the combination with the main frame, of an arched supporting-axle comprising separate wheel-sections and a horizontal, hollow crown-section into which the ends of the wheel-sections adjustably extend, brackets carried by said horizontal section and secured to the side bars of the main frame, 20 beam-supporting arms pivoted to said brackets and means for locking the separate sections of the axle together.

13. In cultivators, the combination with the main frame, of an arched supporting-axle comprising separate wheel-sections and a central, hollow crown-section adapted to adjustably receive the ends of said wheel-sections, brackets clamped upon the ends of said horizontal sections and secured to the side bars of the 25 frame, rotatable collars adjustably secured to the upper, horizontal portions of said wheel-sections, said collars engaging slots in said brackets and adjustable connections between the lower ends of said wheel-sections and the 30 main frame.

14. In riding-cultivators, the combination with the main frame, of an arched axle comprising a central, tubular section and depending wheel-sections horizontally swiveled and 40 laterally adjustable in said horizontal section, rotatable collars adjustably secured to the upper, horizontal portions of said wheel-sections, brackets secured to said horizontal section and embracing said collars to prevent their lateral 45 displacement, a rock-shaft journaled on said frame in front of said axle, depending rock-arms on said shaft, links connecting said rock-arms and the lower portions of said wheel-sections, an operating-lever for said rock-shaft 50 extending rearwardly within reach of the rider and means for locking said lever in adjusted position.

15. In cultivators, the combination with the main frame and the shovel-beam hung therefrom, of an arched supporting-axle swiveled 55 to the frame and having depending wheel-sections, a rock-shaft journaled on the frame and connected to said wheel-sections, a shift-lever loosely journaled on said rock-shaft and connected to said shovel-beam and means for independently adjusting said rock-shaft and said shift-lever.

16. In riding-cultivators, the combination with the main frame and with the shovel-beams

hung therefrom, of an arched supporting-axle 65 swiveled to the frame and having depending wheel-sections, a rock-shaft journaled on the fore part of the frame, rock-arms on said shaft connected to said wheel-sections, shift-levers loosely journaled on said rock-shaft and connected to said shovel-beams, independently-movable operating-handles for said rock-shaft and said shift-levers extending rearwardly within reach of the rider and means for locking said operating-handles in adjusted position. 70 75

17. In cultivators, the combination with the main frame and shovel-beams hung therefrom, of an arched supporting-axle having 80 separate wheel-sections, a rock-shaft journaled at the fore part of the frame, rock-arms fixed to said shaft and connected to said depending wheel-sections, radius-arms pivoted to the frame and connected to the rear ends of said shovel-beams, shift-levers loosely journaled on said rock-shaft, spring-regulators extending between said shift-levers and said radius-arms and independent operating-handles for said shift-levers and said rock-shaft under 85 control from the driver's seat. 90

18. In cultivators, the combination with a cross-bar at the front of the frame, of a sleeve on said bar, a vertically-disposed sleeve within which the forward end of the cultivator-beam is swiveled, overlapping vertically-disposed 95 lugs on said sleeves, a horizontal cross-bolt extending from side to side through said lugs upon which said vertical sleeve is arranged to oscillate and means for holding said vertical sleeve against oscillation. 100

19. In cultivators, the combination with a cross-shaft at the front of the frame, a sleeve on said shaft, a vertically-disposed sleeve within which the front end of the cultivator-beam is journaled, a pair of laterally-extending lugs 105 on one of said sleeves, a lug on the other sleeves projecting between said pair of lugs, a cross-bolt extending through said lugs whereon said vertical sleeve is arranged to oscillate, projections on said sleeves arranged side by side and a bolt extending through said projections. 110

20. In cultivators, the combination with a cross-shaft at the front of the frame, of a sleeve mounted on said shaft and provided with a 115 pair of laterally-extending lugs, a vertically-disposed sleeve within which the forward end of the cultivator-beam is journaled, a laterally-extending lug on said vertical sleeve, elliptical in section and projecting between said pair of lugs, a cross-bolt connecting said lugs, projections on said sleeves and a bolt-and-slot connection between said projections. 120

21. In cultivators, the combination with the beam and the suspension-rod therefor, of a 125 bracket pivotally secured to said beam to swing forward and back, a suspension-rod pivoted to said bracket to swing crosswise rela-

tively thereto and means for clamping said bracket and suspension-rod together.

22. In cultivators, the combination with the cultivator-beam, of a cross-bolt connecting the 5 separate members of said beam, a bracket swiveled on said cross-bolt, a spacing-sleeve surrounding said bolt and extending through said bracket into engagement with the sepa-

rate members of said beam, a suspension-rod pivoted at its lower end to said bracket and a 10 bolt-and-slot connection between said bracket and said suspension-rod.

WILLIAM SOBEY.
